DESIGN FOR A DRESS

Morris Massow, New York, N. Y.

Application August 25, 1937, Serial No. 71,314

Term of patent 3½ years

To all whom it may concern:

Be it known that I, Morris Massow, a citizen of the United States, residing at 2675 Crescent Avenue, in the county of the Bronx, city and State of New York, have invented a new, original, and ornamental Design for a Dress, of which the following is a specification, reference being had to the accompanying drawing, constituting a part thereof.

I claim:

The ornamental design for a dress, substantially as shown.

MORRIS MASSOW.
